INVENTOR

Howard E. Swift,
BY
John Morgan
ATTORNEY

UNITED STATES PATENT OFFICE

HOWARD E. SWIFT, OF WESTFIELD, MASSACHUSETTS

LANDING GEAR

Application filed August 15, 1929. Serial No. 386,053.

This invention relates to a landing gear and has relation more particularly to a mechanism of this kind especially designed and adapted for use in conjunction with a semi-trailer, and it is an object of the invention to provide a gear of this kind which, when not in use, may be readily folded or compacted and wherein it is so constructed that when folded or compacted the various parts are so balanced that no lock is required.

Another object of the invention is to provide a mechanism of this kind which in its folded or compacted adjustment may be readily caused to drop into operative or working position under the influence of strain imposed thereon, such as a push with a foot on the hub of a landing wheel sufficient to carry the load of the folded or compacted gear beyond its center.

A still further object of the invention is to provide a device of this kind which, when its working or operative adjustment, affords a solid frame from the trailer to the ground and which embodies a construction requiring but a single brace for each of the landing wheels.

An additional object of the invention is to provide a mechanism of this kind which can be readily folded or compacted when not in use and wherein the structure is such that the load of the mechanism when folded or compacted is balanced by a spring and whereby such folded or compacted mechanism may be readily and conveniently dropped into working or operative position under the influence of strain imposed thereon by the foot of a person.

The invention consists in the details of construction and in the combination and arrangement of the several parts of my improved landing gear whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to de-

scribe the same with reference to the accompanying drawings, wherein:—

Figure 1 is a view in side elevation of a landing gear constructed in accordance with an embodiment of my invention, the associated portion of the frame of a semi-trailer being shown in fragment;

Figure 2 is a view partly in section and partly in elevation and looking in the direction of the arrows as indicated by the line 2—2 on Figure 1;

Figure 3 is an enlarged fragmentary view partly in section and partly in elevation of a knee joint and its associated parts as herein disclosed.

Figure 4 is a side elevation of the embodiment shown in Figure 1 and showing the landing gear in elevated or running position.

As disclosed in the accompanying drawings, 1 denotes a portion of a side member of the frame of a semi-trailer with which my improved landing gear is adapted to be coupled. This member 1 at desired points spaced lengthwise thereof has suitably anchored thereto the depending brackets 2 and 3. An elongated leg 4, preferably tubular, has its upper end portion freely engaged with a cross bar 5, each end portion of which being operatively supported by a bracket 2. The opposite or lower portion of the leg 4 carries a sleeve or barrel 6 which snugly and freely surrounds an end portion of the stub shaft 7 extending out from the adjacent end of the lower cross member 8. The stub shaft 7 has rotatably mounted thereon a landing wheel 9.

In Figure 2 of the accompanying drawings only one side portion of the device is illustrated and it is to be understood that the structure as disclosed by this figure is duplicated at the opposite side of the trailer frame.

Approximately midway its ends the bar 5 has fixed thereto an end portion of a forwardly and downwardly directed lever arm 10, the forward and lower end portion of which is pivotally connected, as at 11, with an end portion of a locking lever 12. This lever is disposed inwardly and downwardly and has its opposite or lower end portion pivotally connected, as at 14, with the outer end portion of a lock lever tripping arm 15. The

adjacent end portions of the lever 12 and arm 15 adjacent their pivotal connection 14 coact to form a toggle joint 16, to permit said joint to break upon upward movement 5 of the pivotal connection 14, but limiting the extent of relative movement of said lever 12 and arm 15 when said pivotal connection 14 is moved downwardly and particularly to prevent said pivotal connection 14 passing 10 beyond a longitudinal alignment of the lever 12 and arm 15 when the landing gear is dropped.

The tripping arm 15 is clamped or otherwise securely affixed, as at 17, to a cross bar 18 which is common to the knee joints at opposite sides of the trailer frame.

Each of the knee joints comprises two blocks 19 and 20, adjacent ends of which abutting, as at 21, (Figure 3), when said blocks are in alignment. These blocks 19 and 20 are provided respectively with the oppositely disposed reduced extensions 22 and 23. The block 19 is provided with the angularly disposed and rearwardly directed spaced ears 24 between which is received the angularly disposed ear 25 carried by the second block 20, said ears 24 and 25 being in pivotal connection with the cross bar 18. By this means, the blocks 19 and 20 are supported for relative swinging movement upon upward travel of the bar 18, the downward travel of such bar 18 being limited upon the opposed ends of the blocks 19 and 20 abutting at 21. In other words, each knee joint is capable of breaking only in one direction and that upwardly.

Each knee joint is arranged inwardly of and in relatively close proximity to a leg 4. The extension 22 of the block 19 is welded 40 within or otherwise secured to the lower end portion of an elongated tubular thrust member 26. The opposite or upper end portion of the member 26 has secured thereto a laterally disposed arm 27 terminating in an 45 upstanding lug 28 which is pivotally engaged to the rear bracket 3 through the instrumentality of the cross bar 29. This cross bar 29 is common to the bracket 3 at each side of the trailer frame.

50 The extension 23 of the second block 20 is welded or otherwise secured within the upper portion of a second elongated tubular thrust member 30, the lower end portion of which carrying a sleeve or cuff 31 completely 55 surrounding the cross member 8.

The bar 29 at a desired point intermediate its ends has operatively engaged therewith a depending spring swivel block 32 through which is freely directed an elongated shank 60 33. Threaded upon the shank 33 are the nuts 34 for coaction with the rear end of the block 32 whereby the extent of projection of the shank 33 forwardly of the block 32 may be adjusted as required to regulate 65 the tension of the load balancing spring 35.

As herein embodied, the load balancing spring 35 is of a coil type and has one end portion engaged with the hook 36 provided at the forward end of the shank 33 while the opposite end portion of the spring 35 is 70 operatively engaged with the hook member 37. This hook member 37 is adapted to be selectively engaged through one of the series of openings 38 spaced lengthwise of the lever arm 10.

75 Freely mounted on the cross rod 18 outwardly of but immediately adjacent to the connection between said rod 18 and the ears 24 and 25 is the hub 39 of a foot lever or pedal 40. The hub 39 is provided with a 80 slot or recess providing circumferentially spaced shoulders 41 between which is arranged an outstanding pin or part 42 carried by the cross rod 18 so that when the foot lever 40 is kicked clockwise, the knee joints 85 will be broken and at the same time the pivotal connection 14 will move upwardly and when the lever arm 10 passes downwardly beyond the vertical the spring 35 will operate to lift the gear up into folded or 90 compacted adjustment. When folded or compacted the tension of this spring 35 will maintain the gear in such compacted or folded adjustment without the necessity of 95 using any locking means.

When it is desired to drop the gear into working or operative position it is only necessary to exert requisite pressure, as by pushing with the foot, upon a wheel 9 or cross member 8 to carry the load back over 100 the center again.

The load, in lifting or compacting the gear, is carried upwardly by an elongated lever 43 having one end portion fixed to the cross bar 5 and disposed downwardly and 105 rearwardly when the gear is in extended or working position. The opposite or lower end portion of this lever 43 has pivotally connected thereto, as at 44, an end portion of an elongated strap 45, the opposite end 110 portion of which being engaged, as at 46, with the cross member 8.

It is believed to be entirely clear that when the lever 12 and arm 15 are in working or effective adjustment as well as the member 115 26 and associated block 30, they are substantially rigid.

From the foregoing description it is thought to be obvious that a landing gear constructed in accordance with my invention 120 is particularly well adapted for use by reason of the convenience and facility with which it may be assembled and operated, and it will also be obvious that my invention is susceptible of some change and modification 125 without departing from the principles and spirit thereof and for this reason I do not wish to be understood as limiting myself to the precise arrangement and formation of the several parts herein shown in carrying 130

out my invention in practice except as hereinafter claimed.

I claim:—

1. In combination with a vehicle frame, a landing gear therefor comprising a cross bar rotatably supported by the frame, a leg operatively engaged with the frame for swinging movement toward or from the frame, ground engaging means operatively engaged with the leg including a second cross bar, a third cross bar carried by the frame at a point spaced from the first cross bar, a thrust member operatively engaged with the cross bar of the ground engaging means, a second thrust member operatively engaged with the third named cross bar, a knee joint connecting the adjacent ends of the thrust members including another cross bar, a lever arm fixed to the first named cross bar, means engageable with the lever arm for constantly urging the same in one direction, a lever operatively engaged with the lever arm, a tripping arm operatively engaged with said first named lever and with the cross bar comprised in the knee joint, a lifting lever fixed to the first named cross bar, and a strap operatively connected to the lifting lever and to the cross bar comprised in the ground engaging means.
2. In combination with a vehicle frame, a landing gear therefor comprising a cross bar rotatably supported by the frame, a leg operatively engaged with the frame for swinging movement toward or from the frame, ground engaging means operatively engaged with the leg including a second cross bar, a third cross bar carried by the frame at a point spaced from the first cross bar, a thrust member operatively engaged with the cross bar of the ground engaging means, a second thrust member operatively engaged with the third named cross bar, a knee joint connecting the adjacent ends of the thrust members including another cross bar, a lever arm fixed to the first named cross bar, means engageable with the lever arm for constantly urging the same in one direction, a lever operatively engaged with the lever arm, a tripping arm operatively engaged with said first named lever and with the cross bar comprised in the knee joint, a lifting lever fixed to the first named cross bar, a strap operatively connected to the lifting lever and to the cross bar comprised in the ground engaging means, and a foot lever operatively engaged with the cross bar of the knee joint and coacting therewith to break said joint upon movement of said foot lever in one direction.
3. In combination with a vehicle frame, a landing gear therefor comprising a cross bar rotatably supported by the frame, a leg operatively engaged with the frame for swinging movement toward or from the frame, ground engaging means operatively engaged with the leg including a second cross bar, a third cross bar carried by the frame at a point spaced from the first cross bar, a thrust member operatively engaged with the cross bar of the ground engaging means, a second thrust member operatively engaged with the third named cross bar, a knee joint connecting the adjacent ends of the thrust members including another cross bar, a lever arm fixed to the first named cross bar, means engageable with the lever arm for constantly urging the same in one direction, a lever operatively engaged with the lever arm, a tripping arm operatively engaged with said first named lever and with the cross bar comprised in the knee joint, a lifting lever fixed to the first named cross bar, a strap operatively connected to the lifting lever and to the cross bar comprised in the ground engaging means, the trip arm and the lever connected thereto having coacting means for limiting the relative movement thereof in one direction.
4. In combination with a vehicle frame, a landing gear therefor comprising a cross bar rotatably supported by the frame, a leg operatively engaged with the frame for swinging movement toward or from the frame, ground engaging means operatively engaged with the leg including a second cross bar, a third cross bar carried by the frame at a point spaced from the first cross bar, a thrust member operatively engaged with the cross bar of the ground engaging means, a second thrust member operatively engaged with the third named cross bar, a knee joint connecting the adjacent ends of the thrust members including another cross bar, a lever arm fixed to the first named cross bar, means engageable with the lever arm for constantly urging the same in one direction, a lever operatively engaged with the lever arm, a tripping arm operatively engaged with said first named lever and with the cross bar comprised in the knee joint, a lifting lever fixed to the first named cross bar, and a strap operatively connected to the lifting lever and to the cross bar comprised in the ground engaging means, the knee joint comprising means limiting the relative movement of the thrust members in one direction.
5. A semi-trailer landing gear including in combination a vehicle frame, a support for one end of the semi-trailer pivotally mounted on the under side of the frame, a locking toggle for bracing the support, a lever for breaking the toggle and spring means for swinging the support to raise it to running position.
6. A semi-trailer landing gear including in combination a vehicle frame, a support for one end of the semi-trailer pivotally mounted on the under side of the frame, a locking toggle for bracing the support and preventing its movement while supporting the semi-trailer, a manually-operable lever for breaking the toggle and means for swinging the pivotally mounted support to raise it to running position.

7. A semi-trailer landing gear including in combination a vehicle frame, a support for one end of the semi-trailer pivotally mounted on the under side of the frame and adapted to be swung from trailer-supporting to running position, a toggle connecting the lower end of the pivoted support with the frame for bracing the support when in lowered position, manually operated levers for breaking the toggle and spring means for raising the support to running position.

8. A semi-trailer landing gear including in combination a vehicle frame, a support for one end of the semi-trailer pivotally mounted on the under side of the frame, a locking toggle for bracing the support, a lever for breaking the toggle and spring means for swinging the support to raise it to running position, said spring being connected at its ends on either side of the toggle joint to hold the toggle in locking position until release.

In testimony whereof I hereunto affix my signature.

HOWARD E. SWIFT.
